US00D761819S

(12) United States Design Patent
Lee et al.

(10) Patent No.: US D761,819 S
(45) Date of Patent: * Jul. 19, 2016

(54) DISPLAY SCREEN OR PORTION THEREOF
WITH GRAPHICAL USER INTERFACE

(71) Applicant: Samsung Electronics Co., Ltd.,
Suwon-si (KR)

(72) Inventors: Seunguk Lee, Goyang-si (KR);
Changwon Kim, Asan-si (KR); Sunmi Jin, Yongin-si (KR)

(73) Assignee: Samsung Electronics Co., Ltd.,
Suwon-si (KR)

() Term: 14 Years

(21) Appl. No.: 29/517,385

(22) Filed: Feb. 12, 2015

(30) Foreign Application Priority Data

Aug. 28, 2014 (KR) 30-2014-0042067

(51) LOC (10) Cl. 14-04

(52) U.S. Cl.
USPC D14/485

(58) Field of Classification Search

USPC D14/485-495; 715/763, 810, 836, 837,

(57) CLAIM

We claim the ornamental design for a display screen or portion thereof with graphical user interface, as shown and described.

DESCRIPTION
